[57] CLAIM

The ornamental design for a display package, substantially as shown and described.

DESCRIPTION

FIG. 1 is a front elevational view of a display package embodying my new design;

FIG. 2 is a left side elevational view thereof;

FIG. 3 is a rear elevational view thereof;

FIG. 4 is a right side elevational view thereof;

FIG. 5 is a top view thereof; and

FIG. 6 is a bottom view thereof.

The broken lines showing a packaged article in FIGS. 1, 2 and 5 are for the purpose of illustrating environmental use only.

FIG. 4.

FIG. 5.

FIG. 6.

FIG. 2.

FIG. 1.

FIG. 5.
